UNITED STATES PATENT OFFICE

MAX POPPER, OF NEW YORK, N. Y.

VENTILATING STRIP FOR HATS

Application filed October 4, 1928. Serial No. 310,421.

This invention is directed to an improvement in self-conforming, ventilating sweat bands for hats, caps, and other head wear, wherein simple and economical provision is made for the comfortable fit of the hat while at the same time affording complete ventilation of the space within the hat above the head.

Ventilating sweat bands of this character have been before proposed, but such, so far as known, have been so constructed as to permit shifting of the sweat band proper in the continued use of the hat, with the effect to more or less completely close the ventilating openings and thus defeat the ventilating function; and, furthermore, present difficulties and require unnecessary labor in securing the ventilating strip and hat-connecting strip together and to the hat.

An essential and primary object of the present invention, is, therefore, the provision of a ventilating strip integrally constructed to prevent collapse under any and all conditions of use, to thereby maintain the ventilating function as long as the strip is in place.

A further object is to construct the ventilating strip to facilitate the connection of the hat-connecting strip thereto, where such latter strip is a separate element, and to provide the ventilating strip with an integral hat-connecting strip for use where the separate hat-connecting strip is to be dispensed with.

A further object is the provision of a ventilating strip formed with flap extensions, one of which provides for the connection of the sweat-band proper thereto, while the other of which, in some instances, provides for direct connection to the hat, and in other instances provides for the connection of a connecting strip to be in turn connected to the hat.

A further object is the provision of a ventilating strip integrally formed to insure full ventilating openings substantially throughout the full height of the strip without interfering with the functions of the flap extensions and without requiring a comparatively costly and bulky construction.

The invention is illustrated in the accompanying drawings, in which:

Fig. 1 is a broken bottom plan view of a hat with the ventilating sweat band in place.

Fig. 2 is a view of the ventilating strip with the sweat band proper secured thereto, the view being taken from the face side of the sweat band.

Fig. 3 is a similar view taken from the opposite side of the sweat band.

Fig. 4 is a section on the line 4—4 of Fig. 1.

Fig. 5 is a perspective view of the ventilating strip shown in Figs. 1 to 4.

Fig. 6 is a perspective view of a modified form of ventilating strip.

Fig. 7 is a similar view showing the modified form of Fig. 6 formed with a sweat-band receiving shoulder.

Fig. 8 is a perspective view of another form of ventilating strip.

Fig. 9 is a perspective view of a further form of ventilating strip.

Fig. 10 is a plan of the form shown in Fig. 9.

Fig. 11 is a perspective view of another form of the invention.

In the form of the invention shown more particularly in Figs. 1 to 5, the ventilating strip, which is preferably constructed of soft rubber or the like, comprises a narrow central section 1, which may be described as including spaced walls 2, connected by transverse webs 3 to define ventilating openings 4. This central section is provided at one side with a comparatively narrow flap 5, extending through the length of the section in line with the bottom thereof. The opposite side of the central section has a similar flap 6, extending in line with the bottom of the central section, but of materially greater dimensions beyond the central section than the flap 5. The flap 6, some distance beyond the connection of the flap and section 1, is integrally formed or otherwise provided with block-like spacing elements 7, which have a projection beyond the surface of the flap approximately equal to the width of the section 1, and which while relatively spaced, may be arranged in line with the webs 3 of the section 1, or in line with the openings 4.

In the use of this form of the ventilating section, a narrow strip 8, preferably of fab-

ric is cemented or otherwise secured to the upper surface of the flap 5, the strip 8 projecting beyond the free edge of the flap 5. When thus arranged, the free edge of the flap 5 projects beyond the surface of the strip 8 to form a shoulder 9. The sweat band proper 10 is then secured to the strip, the lower edge of such sweat band bearing on the shoulder 9. As the width of the shoulder 9 is substantially that of the thickness of the sweat band 10, the construction provides in a simple and inexpensive manner for the junction of the sweat band and ventilating strip without undue projection at the joint, which would otherwise provide an objectionable ridge which would be uncomfortable in the use of the hat.

The flap 6 is then secured to the hat, this flap providing the connecting strip between the sweat band and hat. In this connection, the flap 6 may be cemented to the hat or secured thereto in any desired or conventional manner. The sweat band 10 is preferably secured to the strip 8 by stitching 11, indicated in Fig. 2, and this stitching may be of ornamental character as usually provided in hat construction. After the parts are connected, as described, the sweat band is turned inside the hat 13 in the conventional position. Thus the sweat band is turned over the flap 6, and such sweat band, or more properly the strip 8 is brought into contact with the spacing elements 7. These elements serve to form ventilating spaces or channels 14 above the openings 4, which cannot be closed under usual pressure on the sweat band, and thus the possibility of closing the openings 4 as ventilating openings by head pressure on the sweat band tending to force said sweat band against the inner surface of the hat, is entirely prevented; and free ventilation is assured at all times.

The spacing elements 7 being of soft rubber, where the ventilating strip is so constructed, permit a yielding at desired points under head pressure, without, however, permitting complete collapse. On relief of the pressure the spacing elements are restored to normal relation to maintain the proper ventilating function.

In ventilating strips for some types of head wear, as in caps and the like, there is no practical necessity for the spacing elements 7 of the preferred form of the invention, nor, due to the complete flexibility of the cap material, any particular necessity for the shoulder 9. Under these requirements, the sweat band, which is itself comparatively narrow may be secured directly to the ventilating strip. For these and similar uses, the sweat band ventilating strip is formed as shown in Fig. 6. Here the central section 14', is of the type described in connection with the preferred form, including walls 15, connected by webs 16, to form openings 17. The cen-

tral section of this form is provided with similar integral flaps 18 and 19 projecting in opposite directions from the central section in line with the bottom thereof. In applying this type of ventilating strip, the sweat band is secured directly to the lower surface of one of the flaps, as 18, while the other flap is secured directly to the hat. The manner and means of making these attachments is unimportant so far as the present invention is concerned, as cementitious material may be used, or stitching employed at the option of the manufacturer.

It is of course to be understood, that if desired the form of the invention shown in Fig. 6 may be provided with an equivalent of the shoulder 9 of the preferred form, by slightly thickening the flap 18 for example, near the connection of the flap and section 14, thus providing the shoulder 20, indicated in Fig. 7. The form in Fig. 7 is identical with the form shown in Fig. 6, other than as to the shoulder 20. The shoulder 20 serves the same purpose as the shoulder 9 in the preferred form.

In order to simplify and cheapen the cost of the ventilating strip, without sacrificing any of its advantages, such strip may be formed as shown in Fig. 8. Here the ventilating strip is a flat sheet of rubber or the like, as 21, punched or cut on the median line to form openings 22, the portions of the sheet in both directions beyond the openings 22 forming the flaps 23 and 24 which are desirable features of the improved ventilating strip in all forms. One of the flaps of the form shown in Fig. 8 is formed in line with the bridges 25 between the openings 22, with block-like spacing elements 26 and 27. The blocks 26 are spaced longitudinally of the ventilating strip, and are disposed at the line of juncture between the particular flap and the bridges. The blocks 27 are also spaced longitudinally of the ventilating strip and also spaced from the blocks 26.

Thus when the flaps are turned upwardly, as in the use of the ventilating strip, the blocks 26 rest on the bridges 25 and form abutments to maintain the openings 22 fully open. The blocks 27 abut the opposite flap and form with the blocks 26 ventilating channels in line with the openings 22. This type of ventilating strip is simple and economical in manufacture, and thoroughly effective in use.

If the ventilating strip is designed for use in silk hats, for example, it is advisable to provide a somewhat more substantial resistance to the close contact of the flaps of the strip above the central section. To secure this result, the ventilating strip may be constructed as shown in Figs. 9 and 10. Here the form of the strip proper is as shown in Fig. 8, that is, constructed of a narrow sheet of rubber formed with openings 28, separated by bridges. The flaps 29 and 30 pro-

ject in opposite directions beyond the line of openings 28, and one of such flaps, as 30 is formed substantially throughout its full width, with spacing abutments 31, integral with, or otherwise connected to the flap, the inner ends of the abutments being in line with the junction of the flap 30 and the bridges 32. The abutments 31 are in line with and substantially of the same width as the bridges, so that as the flaps are turned up, in the application of the completed article to the hat, the abutments bear on the bridges, and form vertically ranging channels in line with the openings 28. This will insure a more or less free passage for the air to and from the interior of the hat above the head of the wearer, under substantially any pressure to which the band may be subjected in use.

20 It is to be particularly noted that the ventilating openings in all forms, whether in the central section or formed with and by the spacing elements are of square outline, as distinguished from the usual round openings employed in similar articles. The square or angular form tend to greater resistance against closing under pressure, and thus provide a more effective maintenance of the ventilation.

30 In Fig. 11 there is shown a further modification of the invention, in that the central section 33 is formed at one side with a flap 36, by which the ventilating strip may be secured to the hat proper. The opposite side 35 of the central section is formed to provide a shoulder 34, on which the lower end of the sweat band proper 35 is arranged, the sweat band being cemented or otherwise secured directly to the central section.

40 Practically all hats are provided with rattan or wire supporters, which serve to hold or secure the sweat band in place, that is tight against the crown of the hat. In the use of the improved ventilating strip, such rattan or wire supporter may be inserted either between the folds of the strip and the flap, or molded directly in the strip during manufacture thereof, or such supporter may be secured in any manner, as by stitching or cementing on the outside of the ventilating strip.

45 The holes in the central sections of the various forms may, without departure from the invention, be of any desired rectangular form, square or oblong, or other angular outline. The webs defining the holes may, as illustrated in Fig. 6, being at other than a right angle to the walls of the strip, as for example in slanting arrangement, as shown 55 in such figure. This arrangement adds to the resiliency.

50 While preferring that the ventilating strip of this invention in its several forms be constructed of soft rubber, primarily for its resiliency, it is to be understood that such strip

may be made of any and all materials, and either integrally or separately constructed.

Having thus described the invention, what is claimed as new, is:

1. A self conforming ventilating strip having a central section of substantially rectangular outline and formed with openings, a securing flap of less thickness than the similar dimension of the central section and adapted to be turned up into contact with the central section in the use of the strip, a second flap adapted to be turned up into contact with the central section to provide a shoulder substantially in the plane of the top of the section to receive the lower edge of a sweat band. 70

2. A ventilating strip including a perforated central section of sufficient relative thickness to provide an abutment, and side sections of materially less thickness than that of the central section and extended in line with the lower edge of the central section, said central section limiting the upturned positions of the side sections. 85

3. A ventilating strip including a central section and side flaps extending laterally of the central section in the plane of the bottom edge of such central section, the central section being of materially increased thickness relative to the side flaps to provide free side surfaces of the central section against 90 which the flaps may be turned in use, one of the flaps being of greater width than the other. 95

4. A ventilating strip of integral form including a central thickened section and relatively thin side flaps, the central section being formed with openings and providing a limiting abutment for the side flaps when the latter are upturned, and spacing means integral with one of said flaps beyond that area 100 contacting with the central section when the flap is upturned. 105

In testimony whereof I affix my signature.
MAX POPPER.
